UNITED STATES PATENT OFFICE.

ALBERT G. ELVIN, OF SOMERVILLE, NEW JERSEY, AND JOHN L. MOHUN, OF BROOKLYN,
NEW YORK, ASSIGNEES, BY MESNE ASSIGNMENTS, TO FRANKLIN RAILWAY SUPPLY
COMPANY, OF WILMINGTON, DELAWARE, A CORPORATION OF DELAWARE.

CONNECTION FOR LOCOMOTIVE DRIFTING-VALVES.

1,141,111.

Specification of Letters Patent.

Patented June 1, 1915.

Application filed January 15, 1914. Serial No. 812,258.

To all whom it may concern:

Be it known that we, ALBERT G. ELVIN and JOHN L. MOHUN, both citizens of the United States, and residents, respectively, of Somerville, in the county of Somerset and State of New Jersey, and of the borough of Brooklyn, in the county of Kings and State of New York, have invented a certain new and useful Improvement in Connections for Locomotive Drifting-Valves, of which improvement the following is a specification.

This invention relates to means for connecting up the supply of steam for a locomotive drifting valve, and while it may be employed with various forms of drifting valves, it is particularly adapted for use in connection with that type of drifting valve set forth in the prior patent to Martin and Mohun, No. 1,080,290, issued December 2, 1913, in which the valve is operated by the locomotive reverse gear.

When the locomotive is brought into the round house, the steam supply for the drifting valve should be positively closed in order to prevent any possibility of inadvertently admitting a sufficient amount of steam through the same to the engine cylinders to start the engine, and the object of our invention is to connect up the supply of steam for the drifting valve with some other auxiliary device upon the locomotive, such as the engine lubricator, having a manually operated member which must always be adjusted to a given position when the locomotive enters the round house, whereby the manual adjustment of said member shall also operate to positively cut off the supply of steam for the drifting valve.

The improvement claimed is hereinafter fully set forth.

In the accompanying drawings: Figure 1 is a side elevation of a portion of a locomotive, and illustrating one form of apparatus embodying our improvement; Fig. 2, a similar view showing a slight modification; Fig. 3, vertical section of the pressure operated valve shown in Fig. 1; and Fig. 4, a view of the double control globe valve as included in the modification shown in Fig. 2.

According to the construction shown in the drawing, a pipe supplies steam from the boiler turret, 5, for the drifting valve, 1,

which may be of any desired type, and operates to supply a small amount of steam to the engine when the locomotive is running with the throttle closed. There are various other auxiliary devices upon the locomotive, such as the engine lubricator, 6, which must be shut off, or set to a certain position, when the locomotive is brought into the round house, and as shown in Fig. 1, the pipe, 7, supplies steam from the boiler turret to the lubricator for operating the same, and contains a hand operated valve, 8, for shutting off the lubricator when the locomotive is not in use, as when it occupies the round house. The valve or cock, 8, also controls the supply of steam to the pipe, 9, and to the chamber, 11, of the pressure operated valve device, 10, shown particularly in Fig. 3, which is connected directly to the drifting valve pipe, 4, and contains the valve, 14, for closing communication from the turret and pipe, 4, through chamber, 15, to pipe, 4, when said valve is seated. The diaphragm, 12, separates the chambers, 11 and 15, the stem or valve, 14, resting upon the diaphragm and normally supported by the spring, 13, whereby the valve, 14, remains open when the fluid pressures in said chambers on opposite sides of the diaphragm are substantially equal.

When the locomotive is in operation upon the road, the valve, 8, of the lubricator is open, and the steam pressure thus admitted to the chamber, 11, balances the pressure in chamber, 15, so that the spring, 13, holds the valve, 14, off its seat and there is free communication from the turret through pipes, 4^a and 4, to the drifting valve which then operates according to its usual functions. When the locomotive is brought into the round house, the lubricator valve, 8, is invariably closed, thus cutting off the supply of fluid pressure to the chamber, 11, beneath the diaphragm. The steam pressure acting on the valve, 14, and on the diaphragm in chamber, 15, then operates to compress the spring, 13, and causes the closing of valve, 14, upon its seat, thereby positively cutting off all supply of steam to the drifting valve and preventing any accidental starting of the locomotive due to inadvertent admission of steam through the drifting valve.

According to the modification shown in Figs. 2 and 4, we employ a globe valve, 10^a, having a connection with the turret at 3, and controlling communication therefrom to the two pipe connections, 7, leading to the lubricator, and 4, leading to the drifting valve. With this construction, whenever the globe valve is turned to shut off the lubricator, as it always will be when the locomotive is out of service or brought into the round house, the supply of steam to the drifting valve will also be shut off by the same movement which closes the lubricator supply.

15 By means of our improvement, it will now be apparent, all additional care or attention which might otherwise be required to close an extra valve in the drifting valve supply each and every time a locomotive was 20 brought into the round house, is eliminated, and a double safety feature is thus provided, which may be relied upon to prevent any accidents of the character above referred to.

25 Having now described our invention, what we claim as new and desire to secure by Letters Patent is:

1. The combination in a locomotive, of a drifting valve for supplying a limited quantity of steam to the engine when running 30 with throttle closed, an auxiliary device hav-

ing a manually operated member adapted to be set to a certain required position, and means controlled by said manually operated member for cutting off the supply of steam 35 for said drifting valve.

2. The combination in a locomotive, of a drifting valve for supplying a limited quantity of steam to the engine when running with throttle closed, a steam operated lubricating device for the engine, a hand valve for closing the supply of steam to the lubricator, and means controlled by said hand valve for cutting off the supply of steam for the drifting valve.

3. The combination in a locomotive, of a drifting valve for supplying a limited quantity of steam to the engine when running with throttle closed, a fluid pressure actuated valve for controlling the supply of steam for the drifting valve, a steam operated lubricating device for the engine, and a hand valve controlling the supply of steam to the lubricator and to said pressure actuated valve.

In testimony whereof we have hereunto set our hands.

ALBERT G. ELVIN.
JOHN L. MOHUN.
